BUBBLING DRINKING-FOUNTAIN.

1,019,162.

Specification of Letters Patent. Patented Mar. 5, 1912.

Application filed January 25, 1910. Serial No. 539,965.

To all whom it may concern:

Be it known that I, SIMEON C. KEITH, Jr., of Somerville, in the county of Middlesex and State of Massachusetts, have invented 5 certain new and useful Improvements in Bubbling Drinking-Fountains, of which the following is a specification.

This invention has relation to drinking fountains, such as are used in schools and 10 other public places, in which the water bubbles or is discharged upward in a short stream from a nozzle, so that a person assuaging his thirst may put his lips directly to the nozzle and drink the water as it 15 emerges therefrom. Such fountains fulfil all requirements in preventing the spread of contagious or infectious diseases, inasmuch as the stream of water, so far as is known, washes away any germs or microbes which 20 may be left by the person last drinking, and for this reason such fountains have been widely adopted.

In the practical use of such fountains, however, a difficulty has arisen, and this invention has for its object to overcome or remove it. That is to say,—where the fountains are supplied from the same service pipe from which water is delivered to sinks 25 and water-closets and wash basins in the 30 same building, the pressure of the water in the fountain is diminished each time one of the latter is in use, and consequently the height of the stream or bubble varies from time to time. In a school, for instance, the 35 height of the bubble is fixed when the toilet rooms are not in use, and hence at recess, when the water-closets require a practically constant flow of water and the fountains are most in demand, the bubble or jet is reduced 40 to its minimum. On the other hand, were the height of the bubble or jet fixed when all the other fixtures were being used and water being delivered thereto, the pressure 45 in the fountains at normal periods would be so great that the jet or bubble would be too strong and rise to a too great height.

As stated, the object of the present invention is to provide such drinking fountains with means for regulating the water pressure so that the height of the bubble or jet will remain constant at all times. To this end I provide a bubbling fountain head, which may be attached to the end of a service pipe and which is self-contained and self-regulating. It is provided with a nozzle or 50 opening for the emission of the water to

form a jet or bubble, and between said nozzle or opening and an inlet port the head is provided with an instrumentality which so controls the passage of the water to the 30 nozzle that the water delivered to the latter is at a constant pressure irrespective of the pressure in the service pipe.

On the accompanying drawings, I have 65 illustrated two different embodiments of the invention, and doubtless others will suggest themselves to persons skilled in the art to whom this disclosure is made.

Figure 1 of the drawing illustrates a bubbling drinking fountain provided with my 70 invention. Fig. 2 represents a vertical sectional view, full size, of another embodiment of the invention. Fig. 3 represents a horizontal section on the line 3—3 of Fig. 2. Fig. 4 represents a similar section on the 75 line 4—4 of Fig. 2. Fig. 5 represents a vertical section through the base of the cup and shows the throttling valve removed. Fig. 6 is a perspective view of a piston used in my device. Fig. 7 represents a vertical 80 section through the fountain shown in Fig. 1.

It is quite apparent that the invention may be utilized in various standard drinking fountains which are supported by columns or otherwise.

In Fig. 1, I have illustrated somewhat conventionally a sink consisting of a hollow slab *a* having a wall plate *b*. The water which is received in the slab *a* is conducted to the sewer through a discharge pipe *c* having the usual trap. *d* indicates a service pipe through which water is delivered to the nozzle as will be explained.

In the embodiment of the invention shown in Figs. 2 to 6 inclusive, which illustrates a two-part head, the nozzle consists of a cap 95 11 covering a cup or bowl 10, the upper end of which is internally threaded to receive it, said nozzle being provided with an aperture or port 12 for the emission of the water. The lower end of the cup or bowl is reduced in diameter and is externally threaded so as to be screwed into the reduced end 13 of a substantially cylindrical casing 14. The casing is provided with a lateral annular internally threaded flange 15 into which the end of the service pipe is screwed. While the cup and the casing 14 are separable, yet, when connected, they form a single casing, 100 constitute in one instrumentality a bubbling fountain, and inclose the reducing valve to be described. From the interior of the

flange 15 there leads a conduit 16 which terminates at its end in a valve seat having a port 17 communicating with a cylindrical passageway 18. The conduit and passageway are formed by an arm 19 extending inwardly from the cylindrical wall of the casing, and a vertical annular flange 20 at the end of said arm. The water from the service pipe d passes through the conduit 16 and is delivered into the passageway 18 as shown by the arrows. Within the cylindrical chamber is placed a cup piston 21 having a central stem 22 which is encircled by a helical spring 23. The lower end of said spring projects into a socket 24 with which a cap 25, screwed on the lower end of the casing, is provided. The piston is provided with a downwardly tapering valve member 26, the upper end of which fits the passageway 18. The extremity of said valve member is substantially conical so that when the piston is forced downward by the pressure of the water, the port 17 will be gradually closed by said member. In the position shown in Fig. 2, the flow of water through the port 17 is substantially unobstructed by the valve member, but, as the piston moves downward slowly, the flow of water through the port will be gradually diminished until finally it is cut off altogether. A spring of the proper tension having been first obtained, it will be seen that the piston will be forced downward to a sufficient extent to permit a normal flow of water into the lower portion of the casing and thence into the cup or upper portion of the casing from which it will emerge in a bubble or jet through the aperture or port 12. Should the water pressure in the service pipe d be increased, however, the piston will be moved downwardly in accordance with such increased pressure and the valve port 17 will be correspondingly reduced by the downward movement of the valve so that the volume of water delivered to the casing will be unvaried. If, however, the pressure in the service pipe d be decreased, the piston will move upwardly and the port will be open to a greater extent by the valve member, so that in this case likewise the volume of water delivered to the casing will be undiminished.

I interpose between the cup or upper portion of the casing and the chamber in the lower portion of the casing a throttling valve which is indicated at 27. It will be observed that the reduced end of the cup has an internal flange which forms a port 28 between the cup and the chamber. The throttling valve is threaded into the bottom of the cup so that its reduced end is in proximity to the port 28 and consequently by screwing the valve in or out, the port may be more or less throttled. Encircling the screw, the bottom of the cup is provided

with a plurality of reduced apertures 29 through which the water passes from the port 28 to the interior of the cup, as indicated by the arrows in Figs. 2 and 5. The piston 21 has a nice sliding fit in the cylindrical chamber, but, as it is possible that at times some water may leak by it, the cap 25 is provided with an outlet aperture 30 through which said water may drip into the sink.

In Fig. 7, I have shown a much more simple and preferred form of the invention in which the casing forms a single chamber for the piston so that the piston is placed directly in the cup itself. In this case, the cup or bowl is indicated at 31, and, as shown, it consists of a substantially cylindrical casing, being internally threaded at its upper end to receive the cap or nozzle 32 which has the port 33 for the emission of the jet or bubble. The lower end of the cup is reduced, and it is provided with an externally-threaded annular flange or neck 34 which may be screwed into the service pipe d . Leading from the neck to the interior of the casing, there is a port 35 through which the water passes from the service pipe into the cup, and it is this port which is controlled by the tapering valve member 36 which depends from the cup piston 37 located within the cup. The valve member 36 has a tapering portion and also a lower cylindrical end, so that, when the piston rises to its maximum height, the port 35 will be entirely closed. Between the piston and the cap there is placed a helical spring 38 which is held in place by a spindle 39 on the piston, and by a hollow sleeve 40 depending from the cap. The piston itself is provided with a port or aperture 41 through which the water flows from the lower portion of the cup into the upper portion thereof, this port being controlled by a slotted throttling valve 41. With this construction, the water flowing from the service pipe into the cup below the piston, raises the piston against the tension of the spring so as to partially close the port 35 and thus permit the normal flow of water through the aperture in the piston into the cup and thus provide for a jet or bubble of the normal height. Should the pressure in the service pipe be increased, the piston will be raised so as to partially close the port 35, and, if the pressure decrease, the spring 38 will force the piston downward so that the port will be opened to a greater extent.

It will be understood that the service pipe will be provided with the usual key valve by which the janitor or other attendant will cut off the flow when the fountain is not in use.

In both forms of the invention, the casing, with its inclosed regulating valve, is provided with a nozzle for forming a bubble, and constitutes a bubbling fountain,

which, so far as the automatic regulation of the height of the bubble is concerned, is wholly independent of any other fountains or fixtures which may be connected with 5 the same service pipe. Consequently each fountain may be substituted for a faucet or similar fixture, without requiring any material alteration in the service piping, and will deliver at all times a bubble of substantially unvarying height. Moreover in 10 both forms of the invention, the nozzle is immovable with respect to the casing, in the sense that its position is unchanged by varying pressures in the service pipe. All 15 exterior or exposed portions of the head or fitting are rigid or immovable while the device is in operation or is delivering water, the controlling or regulating mechanisms being all covered or contained within the 20 head.

What I claim is:

1. A self-contained self-regulating bubbling drinking fountain head, comprising a cup-like casing forming a chamber and having 25 at its upper portion a nozzle immovable with respect to the remainder of said casing and provided with a port for the emission of a vertical jet or bubble, an inlet port, and yielding means in said chamber having 30 an area exposed to the pressure of incoming water in said chamber and arranged to regulate the flow of water through said inlet port, in consequence of which the bubble or jet emitted from the outlet port is of substantially unvarying height irrespective of 35 the pressure of water entering said casing.

2. A self-contained self-regulating bubbling fountain head, comprising a substantially upright casing having at its upper 40 end an immovable nozzle apertured for the emission of a jet or bubble, and a port communicating with said nozzle, and means located within said casing controlled by the pressure of the water for partially opening 45 or closing the said port and thereby maintaining a constant jet or bubble at a predetermined height.

3. A self-contained self-regulating bubbling drinking fountain, comprising a casing 50 having at its lower portion an inlet port

with which the service pipe may be connected, a nozzle at its upper end having a centrally located outlet port or aperture for the emission of a substantially vertical jet or bubble, a valve member for controlling 55 the flow of water through said port, a piston in said casing connected to said valve member, and a spring in said casing which bears against said nozzle and said piston to oppose the pressure of the water against 60 said piston, whereby the pressure of water in said casing is kept substantially unvaried irrespective of the variations in the pressure of water in the service pipe leading to 65 said inlet pipe.

4. In a bubbling drinking fountain, a cup having at its upper end a nozzle with an outlet port for the emission of a substantially vertical bubble or jet, and having at 70 its lower end an inlet port, and means located within said cup for maintaining a constant water pressure in said cup, said means comprising a valve seat having an inlet port, a reducing valve member for controlling said port, and a spring-tensioned 75 piston located between said ports connected to said reducing valve member and receiving the pressure of water admitted to said valve through said inlet port, there being 80 a water duct through said piston.

5. A self-contained self-regulating bubbling fountain, comprising a casing having at its lower end an inlet port formed with a valve seat, and having at its upper end a nozzle with an outlet port or aperture for the emission of a substantially vertical jet or bubble, said nozzle having an annular flange extending into the fountain through which the water flows to said port or aperture, an apertured piston in the casing and 85 having a reduced valve member cooperating with the said inlet port and valve seat, and a spring encircling said flange and bearing against the said piston.

In testimony whereof I have affixed my signature, in presence of two witnesses.
